UNITED STATES PATENT OFFICE.

ROBERT H. DIMOCK, OF ST. LOUIS, MISSOURI.

PIPE.

1,098,485.

Specification of Letters Patent.

Patented June 2, 1914.

Application filed January 22, 1913. Serial No. 743,647.

To all whom it may concern:

Be it known that I, ROBERT H. DIMOCK, a citizen of the United States, residing at St. Louis, State of Missouri, have invented 5 new and useful Improvements in Pipes, of which the following is a specification.

The present invention relates to the class of pipes and the provision of a device of this character comprising a removable, reversible bowl. The advantages derived from a device such as this are readily educed. It allows the same to be smoked almost continuously without lighting at each filling, and provides a pipe which may be readily 15 cleaned and thus kept in a sanitary condition. It is apparent that a device of this nature is especially adapted for use in automobileing or boating, however other purposes will be recognized as the description continues.

With the above and other objects in view my invention relates to such details of construction and in the arrangement and combination of parts as will be hereinafter 25 fully described and specifically pointed out in the appended claim.

In describing my invention in detail, reference will be had to the accompanying drawings wherein like characters denote like 30 or corresponding parts throughout the several views and in which—

Figure 1 is a vertical sectional view of the body of the device showing the stem and mouth piece in elevation. Fig. 2 is a view 35 similar to Fig. 1 illustrating the bowl of the pipe removed. Fig. 3 is a sectional view of the bowl of the pipe. Fig. 4 is a detail view of a plug which is used.

Referring now more particularly to the 40 drawings wherein is shown the preferred embodiment of my invention the numeral 10 designates the body portion thereof which as is shown is substantially semi-spherical. The body portion may be constructed of any suitable material, either wood, bone or metal, but in actual practice aluminum has proven 45 very efficient. Formed upon the upper level face of the body portion is an upstanding projection 12, the sides 13 of the same being cut slanting toward the base, as clearly illustrated. While the projection may be formed 50 integral with the body portion as illustrated in the drawings it may also be secured thereto by any suitable means. The body portion 55 and projection are further provided with a vertically extending opening 11 through

which the smoke from the bowl travels when the same is in use.

Consistent with the foregoing remarks I have provided an improved form of bowl, 60 consisting of a body portion 14, the interior bore thereof being beveled at its extremities as shown at 15 for providing suitable cam faces for frictional engagement with the slanting face 13 of the projection 12. It 65 is recognized that both ends of the bowl are constructed in exactly the same manner, thus allowing the same to be reversed when it is desired, and when in place held in secure frictional engagement with the body portion 70 of the device.

For the purpose of receiving a quantity of packing material 17, such for instance as cotton, the body portion 10 is provided with a recess 16, the latter being disposed centrally therein and communicating with one side thereof as is shown. A stem 18 has connection with the body portion, and extends into a portion of the recess 16, so that its inner face engages the packing material and 80 form a comparatively tight joint. The stem also has a longitudinally extending smoke way 18' formed therein through which the smoke from the bowl of the pipe travels. The mouth piece 19 is further provided which is preferably formed of amber or hard rubber, the latter also having a smoke way 19' formed therein and an exterior screw threaded extension 20 in engagement with the stem. With this arrangement a pipe is provided which is comparatively light, and in view of the fact that the parts are very simple, it may be manufactured and placed upon the market at a 85 minimum cost.

I have provided a member 21 carrying a wedge-shaped extension 22, the latter being received into the lower end of the opening 11 for normally closing the same. By providing this removable plug it is recognized 90 that the cleaning of the pipe is facilitated to an appreciable degree.

The reversibility of the bowl is readily recognized. The tobacco is disposed in the same in the usual manner, and after it has 105 been smoked nearly out new tobacco may be disposed on top of this and the bowl reversed, thus continuously providing a fresh smoke without lighting the pipe at each filling. This function makes the pipe very 110 advantageous for the uses set forth and in view of the fact that its cleaning is facil-

tated, it can always be kept in a sanitary condition.

From the foregoing it is thought that the advantages and novel features of my invention will be readily recognized.

Having thus fully described my invention what I claim as new and desire to secure by Letters Patent is:

A tobacco pipe comprising a body portion 10 having an annular projection formed upon the upper surface thereof, the sides of said projection being beveled, said body portion and said projection having a centrally disposed vertically extending passage way 15 therethrough, a plug inserted in the lower end of said passage way, said body portion

further provided with an inwardly transversely extending recess, said recess intersecting said passage way, packing material in said recess, a stem inserted in said recess and bearing against said packing material, and a removable reversible bowl mounted on said body portion the interior bore thereof of being beveled outwardly at its extremities and frictionally engaged upon the beveled sides of said projection for maintaining the bowl in position. 20 25
